(57) **CLAIM**

The ornamental design for a guitar body, as shown and described.

DESCRIPTION

FIG. 1 is a front isometric view of a guitar body showing my invention;

FIG. 2 is front elevational view of the guitar body of FIG. 1;

FIG. 3 is a left side elevational view of the guitar body of FIG. 2;

FIG. 4 is a right side elevational view of the guitar body of FIG. 2;

FIG. 5 is rear elevational view of the guitar body of FIG. 1; FIG. 6 is a bottom plan view of the guitar body of FIG. 2; and,

FIG. 7 is a top plan view of the guitar body of FIG. 2. The broken line showing of a neck of fingerboard and strings is for illustrative purposes only and forms no part of the claimed design.
